ABSTRACT OF THE DISCLOSURE

Within the drainage trough of an open-curtain water-cooled mold for electroslag refining there is set up, at a small distance from the mold wall, a barrier defining an open-topped annular space. Cooling water is introduced, preferably tangentially, into the space so as to create a flow of water which is closely confined against the mold wall and is in vigorous movement until it overflows the barrier. This is to avoid inadequate cooling due to pockets of stagnant water and/or air at the bottom of the mold wall and consequent breakouts of slag and metal and/or welding of the ingot to the mold wall.

Background of the invention

This invention relates to the so-called electroslag process of producing ingots of refined metal, which word is used herein as connoting not only elemental metals but also, in accordance with an important present day use of this process, metal alloys such for instance as various types of steel.

In the electroslag process, a consumable electrode of the metal to be refined, or possibly of the unalloyed constituents of an alloy to be produced in refined form, is melted into a pool of molten slag, in a water-cooled mold, the metal resolidifying to form an ingot. The process was previously carried out in a water jacketed copper mold, but a recent improvement has been the use of a thin wall steel mold cooled by an open curtain of water flowing freely down its outside. Such a mold is not only less expensive but is also safer in operation, since the effectiveness of the cooling can be observed and steps taken to correct any local overheating. If breakout does occur, the water is at atmospheric pressure and there is no confined jacket or chamber in which dangerous vapour or gas pressures can be generated. Repair is simple and cheap.

The water is collected in a drainage trough round the base of the mold, after it has run down the side of the mold, and it is found that there tends to be a pocket of relatively stagnant water at the corner formed by the mold wall and the base of the trough. With a drainage system in which water collects to a depth of 1"-2" in the trough, the curtain of water, freely falling under gravity and restrained by the drag of the mold side, does not strike the surface of the accumulated water with sufficient velocity to disturb it effectively. Even with a very effective drainage system which may have a drain hole in the base of the trough and in which the water may possibly be only a fraction of an inch deep at the base of the mold, the water flowing down the mold wall is unlikely to cool sufficiently effectively the necessarily sharp corner between the wall and the base: the water may rebound from the base of the trough, forming air pockets and voids.

The mold is in itself open-bottomed but is seated on a water-cooled closure base from which it can be separated to give access to the ingot at the end of the process. During the start of the process, very intense heat is liberated

2

in the mold base and breakouts of slags and metal and welding of the newly formed ingot to the mold are likely to occur if steam pockets are allowed to form at this critical bottom corner. The present invention seeks to eliminate or reduce the formation of such pockets.

Summary of the invention

According to the invention, a mold for electroslag refining is provided with an open-curtain water-cooling system and also has a drainage trough which surrounds a portion of the height of the mold adjacent to its lower end and within which at a small distance from the mold wall there is a barrier defining between itself and the mold wall an open-topped peripheral space, together with means for so introducing cooling water into the space as to create a flow of water which is closely confined against the mold wall by the barrier and militates against the formation of a stagnant water pocket at a corner formed by the mold wall and the drainage trough. Said means may be arranged to direct the cooling water into the space peripherally thereof and preferably, if (as would usually be the case) the space is annular, tangentially thereof so as to establish a circulatory flow.

Brief description of the drawings

In order that the invention may be more clearly understood, an embodiment thereof will now be described by way of example with reference to the accompanying drawing in which:

FIG. 1 is a somewhat schematic cross-sectional elevation of a mold and cooling system therefore in accordance with the invention; and

FIG. 2 is a plan view cross-sectioned on the line A—A in FIG. 1.

Description of the preferred embodiment

Referring to the drawings, the mold is shown at 1, seated on a water cooled closure base 2 with a circular drainage trough 3 surrounding and welded to its lower end. Between the base 2 and the trough 3 there is a sealing gasket 3A: towards its inner diameter, the gasket is composed of some heat resisting material such as asbestos; towards the outer diameter, a more effective sealing material, such as rubber, is employed. A water curtain flowing down the outside of the mold 1 is provided by jets of water spraying on to the outside of the mold from an annular header 4. In accordance with the invention, within the trough 3 an inner circular barrier or wall 5 is set up about 1" away from the mold wall itself. This barrier makes a substantially water-tight joint with the base of the drainage trough and extends upwards for 2"-3" so that its upper edge is above the normal water level in the trough but below the outer boundary wall of the trough. An open-topped annular space 6 is thus formed round the bottom of the mold, and into this space an auxiliary cooling water supply is introduced by means of one or more tangentially approaching pipes 7. This auxiliary supply can conveniently (but not necessarily) be the water discharged from the water cooled base on which the mold rests, as indicated in the drawing by the provision of the linking pipe 8: sometimes this supply may, with advantage, be independent of the supply to the base.

The restricted cross-section of the annular space causes the auxiliary water supply to spiral vigorously upwardly round the mold base, to overflow the barrier 5 into the main drainage trough 3. The water is in vigorous movement against the mold wall until it overflows the barrier, at which point it is joined by the water flowing down the wall. There is thus no point at which water is stagnant and little possibility of the formation of steam pockets: indeed, the water should be supplied sufficiently force-

fully to cause violent agitation thereof against the bottom corner between the mold wall and the trough.

I claim:

1. A mold for electroslag refining provided with an open-curtain water-cooling system and also having a drainage trough which surrounds a portion of the height of the mold adjacent to its lower end and within which at a small distance from the mold wall there is a barrier defining between itself and the mold wall an open-topped peripheral space, together with means for so introducing cooling water into the space as to create a flow of water which is closely confined against the mold wall by the barrier and militates against the formation of a stagnant water pocket at a corner formed by the mold wall and the drainage trough.

2. A mold as claimed in claim 1, with said means arranged to direct the cooling water into the space peripherally thereof so as to establish a circulatory flow.

3. A mold as claimed in claim 2, the space being annular and said means being arranged to direct the cooling water tangentially into the space.

5 4. A mold as claimed in claim 1 arranged for water discharged from a water-cooled base for the mold to be introduced as the cooling water to said space.
